P. G. JACOBSON

CONDENSER

Filed July 5, 1922

UNITED STATES PATENT OFFICE.

PETER G. JACOBSON, OF CHICAGO, ILLINOIS.

CONDENSER.

Application filed July 5, 1922. Serial No. 572,789.

To all whom it may concern:

Be it known that I, PETER G. JACOBSON, citizen of the United States, residing at Chicago, in the county of Cook and State 5 of Illinois, have invented a certain new and useful Improvement in Condensers, of which the following is a full, clear, concise, and exact description.

My invention relates to electrical condensers and has for its object the provision of improved means for effecting the assembly of the leaves which comprise the sides thereof.

In accordance with one characteristic of 15 the invention there is a mounting sleeve having a plurality of sets of arcuate slots distributed along the sleeve, the leaves of one condenser side entering said slots and being recessed to receive the unslotted portion of 20 the sleeve which is formed with interleaving fingers that margin the slots therein. These fingers are preferably of wedge formation whereby they exert pressure upon each other longitudinally of the sleeve upon contraction of the fingers. The spaces between the fingers extend through the material of the sleeve or tube into communication with the bore of the sleeve or tube.

In accordance with another characteristic 30 of the invention the leaves of the other condenser side are provided with a mounting rod and a longitudinally split sleeve embracing said rod and formed with transverse fingers between which portions of these leaves are received whereby they are assembled with said 35 rod. The leaves are desirably provided with aligned recesses through which the mounting rod is passed, there being fingers upon opposite sides of the split in the sleeve so 40 that portions of the leaves which margin both sides of the recesses therein may be received between the fingers upon the sleeve. There are preferably three such rods associated as described.

45 I will explain my invention more fully by reference to the accompanying drawing in which Fig. 1 is a view in elevation, partially in section, of a condenser constructed in accordance with the preferred embodiment of the invention; Fig. 2 is a sectional view on line 2—2 of Fig. 1; Fig. 3 illustrates some of the condenser leaves of one condenser side and parts for assembling the same; Fig. 4 is a view showing the sleeve of fingered formation and some of the condenser leaves assembled therewith; Fig. 5

illustrates some of the condenser leaves of the other condenser side and the fingered sleeve for assembling the same, one condenser leaf being shown in assembly with 60 the sleeve and another in separated relation; and Fig. 6 is an enlargement of a portion of Fig. 2 but before the split sleeve shown in this figure has been clinched into engagement with the rod passing therethrough, the 65 clinching of the sleeve being indicated by dotted lines.

Like parts are indicated by similar characters of reference throughout the different figures.

70 The condenser illustrated includes two mounting plates 1 and 2 of insulating material which are assembled upon threaded metallic rods 3 by means of nuts 4, 5, 6 and 7. These rods are assembled with the mounting board 8, there being distance preserving sleeves 9 that intervene between the nuts 4 and the insulating plate 1. One of the condenser sides is composed of a group of metallic leaves 10 formed with aligned U-shaped recesses 11 through which the mounting rods 3 pass, there being preferably three such mounting rods. A longitudinally split metallic sleeve or tube 12 embraces each rod 3 and is formed with transverse fingers 13 upon opposite sides of the split in the sleeve, these fingers entering the spaces between the leaves. The spaces or slots 14 between the fingers communicate with the interiors or bores of the sleeves and snugly 80 receive the portions of the leaves which margin the sides of the recesses 11 therein. In the process of assembly the split sleeve 12 is preferably initially of U-form as indicated in Figs. 3 and 6, the ends of the fingers 85 being clinched into engagement with the corresponding rod after the sleeve has been placed upon the corresponding rod with the sides of the recess 11 in the slots between the fingers thereof.

100 The other condenser side comprises leaves 15 which are interleaved with the leaves 10 and a metallic mounting sleeve 16. This mounting sleeve has a plurality of sets of arcuate slots distributed along the sleeve, 105 there being three arcuate slots 17, 18 and 19 in each set that are arranged circumferentially of the sleeve. The condenser leaves 15 enter said slots, being formed with leaves 20 and 21 which receive the unslotted portions of said sleeve. Each sleeve is thus 110 formed with a tongue 22 which enters the

middle slot 18 of each circumferential set and wing portions 23, 24 which respectively enter the end slots 17, 19 of such set. The sleeve is formed with a set of fingers 25 upon one side, a set of fingers 26 upon the other side, the fingers of one set interleaving with the fingers of the other and the fingers of both sets tapering or otherwise formed to exert pressure upon one another longitudinally of the sleeve upon contraction of the fingers whereby the portions of the plates that are in the arcuate slots between the fingers are gripped into firm assembly with the sleeve.

15 The leaves 15 are desirably provided with aligned circular holes 27 through which the solid shaft 28 is passed, there being a nut 29 threaded upon the inner end of the shaft 28 whereby the inner ends of the mounting sleeve and shaft are assembled. The inner end of the shaft 28 is continued inwardly beyond the nut 29 to have bearing support in the mounting plate 1 and to be engaged by a spring terminal 30 for including the condenser side 15 in circuit. The nut 31 is threaded upon the other end of the shaft 28 and presses against the adjacent end of the mounting sleeve whereby the assembly of the mounting sleeve and shaft is completed.

20 The shaft 28 projects through the mounting plate 2. A knob 32 has a stem 33 which is threaded upon the projecting front end of the shaft 28. The stem 33 serves to hold the bearing portion 34 between it and the nut 31 this bearing portion turning within the plate 2. There is a rotative mounting for the mounting sleeve when the condenser side carried by the mounting sleeve is to be adjustable, but the invention is not to be thus limited.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

50 1. A condenser having one side formed of a plurality of leaves and a mounting sleeve having a plurality of sets of arcuate slots distributed along the sleeve, there being three slots in each set that are arranged circumferentially of the sleeve, said condenser leaves entering said slots and being recessed to receive the unslotted portions of the sleeve, said sleeve being formed with interleaving fingers which margin the end slots of the slot sets and are formed to exert pressure upon one another longitudinally of the sleeve upon contraction of the fingers.

2. A condenser having one side formed of a plurality of leaves and a mounting sleeve having a plurality of sets of arcuate slots distributed along the sleeve, there being three slots in each set that are arranged circumferentially of the sleeve, said condenser leaves entering said slots and being recessed to receive the unslotted portions of the sleeve, said sleeve being formed with interleaving fingers which margin the end slots of the slot sets.

3. A condenser having one side formed of a plurality of leaves and a mounting sleeve having a plurality of sets of arcuate slots distributed along the sleeve, said condenser leaves entering said slots and being recessed to receive the unslotted portions of the sleeve, said sleeve being formed with interleaving fingers which margin the slots and are formed to exert pressure upon one another longitudinally of the sleeve upon contraction of the fingers.

4. A condenser having one side formed of a plurality of leaves and a mounting sleeve having a plurality of sets of arcuate slots distributed along the sleeve, said condenser leaves entering said slots and being recessed to receive the unslotted portions of the sleeve, said sleeve being formed with interleaving fingers which margin the slots.

5. A condenser having one side formed of a plurality of leaves provided with aligned recesses; a mounting rod passing through said recesses; and a longitudinally split sleeve embracing said rod and formed with transverse fingers upon opposite sides of the split in the sleeve and between which portions of the leaves which margin the sides of their recesses are received, the spaces between the fingers extending through the material of the sleeve into communication with the bore of the sleeve.

6. A condenser having one side formed of a plurality of leaves; a mounting rod; and a longitudinally split sleeve embracing said rod and formed with transverse fingers terminating at the split and between which portions of the leaves are received, the spaces between the fingers extending through the material of the sleeve into communication with the bore of the sleeve.

7. A condenser having one side formed of a plurality of leaves; and a longitudinally split tube formed with transverse fingers terminating at the split and between which portions of the leaves are received, the spaces between the fingers extending through the material of the tube into communication with the bore of the tube.

In witness whereof, I hereunto subscribe my name this 21st day of June A. D., 1922.

PETER G. JACOBSON.
